METHOD AND MEANS FOR ELIMINATING FADING ON SHORT WAVE LENGTHS

Application filed March 15, 1928. Serial No. 261,736.

The invention relates to what is commonly known as fading in radio and wireless signalling and a method and means for eliminating the detrimental effects thereof. The invention particularly adapts itself to the receiving of short waves as transmitted from any appropriate and desired type of short wave radio signalling apparatus and lends itself especially to use in locations where the effects of fading are particularly prevalent and troublesome.

Various theories have frequently been suggested for explanations of the phenomenon known as fading, but it is believed that to date no thoroughly proven theory has been developed. However, certain evidences and phenomena in connection with fading have been discovered in practical observation which have brought out the fact that short wave signals fade differently at points separated by short distances and that the phase relation between signal voltages at these points has been found to be reversed several times per minute. In accordance with these observations, it has been found that signals have different fading characteristics when picked up on antennæ located at different points or upon antennæ located at the same point, where the antennæ each have different directive characteristics. If two antennæ are placed several wavelengths apart, it has been found that at certain periods, signals may be of maximum intensity on one antenna at any particular instant and at the same instant may be of minimum intensity upon the other antenna. This applies likewise to cases where more than two antennæ are used.

It was first thought that it might be possible to carry radio frequency energy picked up upon the several antenna systems in question, to some common receiver and add the energies directly together at this point, but this cannot be done efficiently because it has been found that the phase relation between the signal voltage received at one antenna and that received at another antenna, say 1000 ft. away, does not remain constant, from moment to moment. Therefore, if it is tried to combine a radio frequency voltage from two or more antenna systems located at

points several wavelengths apart, it will be found that these voltages would add at one instant and subtract at another instant due to the fact that the radio frequency voltages at the two antennæ will not hold a definite phase relationship with respect to each other. However, where the receiver is rapidly switched from one antenna system to another as disclosed in our copending applications Serial Nos. 261,737, filed March 15, 1928, and 274,374, filed May 2, 1928, efficient results are obtainable, but this is not a direct combining action.

The important principles to be followed in the multi-antennæ anti-fading methods, which forms a principal object of this invention, is to combine the signals from the plurality of antennæ in such a way that the energies will add irrespective of the phase relationships at the several antennæ, and combine in such a manner that a signal may be heard or recorded in a suitable recording device to produce a signal which is substantially free from the detrimental effects of fading on any of the several antennæ.

The above and other objects form the purpose of this invention which will be more thoroughly understood by making reference to the following specification when read in connection with the accompanying drawing, wherein:—

Fig. 1 illustrates a preferred means for combining the rectified signals from a plurality of spaced antennæ.

Fig. 2 indicates a system similar to that shown in Fig. 1 wherein two antennæ of different directive characteristics, which correspond to the spaced antennæ of Fig. 1, are located at a common point and the energy from the combined output is directed to a limiter and modulator device for the purpose of obtaining a tone signal; and,

Fig. 3 illustrates results which may be accomplished by the efforts and arrangement functioning in accordance with the apparatus diagrammatically illustrated in Figs. 1 and 2.

The subject matter of this application forms a continuation in part of our copending application filed January 2, 1926, Serial

Number 78,768, and is particularly related to Figure 3 thereof.

To now make specific reference to Fig. 1 of the drawing, 1 and 3 represent antennæ which are geographically spaced with respect to each other and are grounded at 5 and 7 respectively. As shown by the drawing, radio frequency energy reaching antennæ 1 and 3 is transferred to radio frequency transformers, or any other preferred form of couplings, 9 and 11 and carried through lead circuits 13 and 15 respectively to receiving devices generally shown as 17 and 19 for each of said separated antennæ members. The receivers 17 and 19 may each employ a common oscillator as shown by Fig. 3 of Serial #78,768, above referred to, or each receiver 17 and 19 may be provided with an independent oscillator, or the energy received upon antennæ 1 and 3 may be detected in the receiver 17 and 19 in the usual manner without the need of oscillator.

The output of the receivers 17 and 19 is amplified in any preferred manner by the use of amplifiers generally designated 21 and 23.

The energy from the amplifiers 21 and 23 is directed to the primary windings 29 and 31 of the transformers 25 and 27, from which 30 it is transferred to the secondaries 33 and 35 and directed to the rectifiers 37 and 39, which each may be biased by a common potential source 49. If desired, the filaments 43 and 45 may be connected in parallel and energized from a single filament battery designated 47.

In series with the common bias potential supply 49 for the plate members of the rectifiers 37 and 39 is a recording device, generally designated 41, which only responds to rectified energy pulses and, therefore, does not differentiate between the phase relation of the radio signal input upon the two receivers 17 and 19. It is, therefore, seen 45 that the recorder 41 responds only to the energy and the matter of phase relationship of the signals reaching the antennæ 1 and 3 is immaterial and has no effect upon the results produced in the recorder 41.

50 As above described for producing a recording action in 41 it is assumed that the switches indicated as 51 and 53 in the plate circuits of the tubes 37 and 39 respectively are closed. However, for the purpose of determining the separate energy reaching each of the receiving circuits including the tubes 37 and 39 we have provided a means for indicating this energy by the separate recorders designated as R1 and R2. In a case where 55 this energy is desired the switches designated as 51 and 53 may be opened and the switches 55 and 57 closed, so that an energy response from each of the signals may be recorded in the recorders R1 and R2. This 60 switching is only resorted to for experi-

mental purposes and for the purpose of determining the separate energy received.

By Figure 3 of the drawing we have shown the result which may be expected by receiving signals on each of the separated antennæ members and represents a portion of typical signal which might be received by placing the recorder R1 or R2 in series with the plates of tubes 37 and 39. To specifically refer to the part of Fig. 3, lettered as "A", 75 it will be noted that the part "d" of the typical case illustrated shows that signals intended to be received upon the antenna system 1 have completely faded out, whereas by making reference to the part "B" of Fig. 3, 80 it will be noted that at a corresponding time period signals have been recorded in the recorder R2 in the case where fading occurred on receiver 17 and recorder R1; but at a different time interval d1 had completely 85 faded out in the recorder R2 associated with the antenna system 3. However, the portion "C" of the tape illustrated by Fig. 3 shows the combined signals received from the two antenna systems 1 and 3 in the recorder 41, 90 and it will be noted that by combining the energy pulses which are totally independent of the phase of the signals reaching the antenna systems 1 and 3 that a signal has been recorded which is accurate and that all portions of the same are clearly legible with the effects of fading on either of the antenna numbers 1 or 3 substantially eliminated. These tapes shown by Fig. 3 illustrate the results which have actually been found in 100 practice and are drawn from actual records which have been made in practice using the above described arrangement.

To now make specific reference to Fig. 2 of the drawing, we have illustrated the form of invention as applicable to a plurality of antennæ of different directive characteristics located at the same point, and, as shown, 101 represents a vertical doublet and 103 a horizontal doublet both located at the same receiving point, and whose respective characteristics vary due to their directive characteristics. Energy from the vertical doublet 101 is directed to a radio frequency amplifier 105, which has not been shown in connection 115 with Fig. 1 although it is to be understood that such amplifier may be added and used if desired. From the amplifier 105 the energy is directed to a receiver 109 where the incoming signals are detected and amplified 120 through an audio frequency amplifier 113 and transferred through the primary winding 121 of a transformer connected with the audio frequency amplifier to the secondary 125 feeding its energy into the rectifying tube 129. Similarly, the energy received on the horizontal doublet 103 is fed to the radio frequency amplifier 107 to the receiver 111 and then through the audio frequency amplifier which transfers its output energy to 130

the primary winding 123 of the transformer 119, where the energy is then transferred to the secondary 127 of the transformer 119 and passed to the rectifying tube 181.

5 The rectifying tubes 129 and 131 are shown as the single filament, double plate type, but two single plate rectifiers may be used with equivalent results. By using full wave rectification, the pulsations of direct current 10 are more uniform, and the ripple frequency is double the audio input frequency, both of which effects make it easier to produce a pure direct current in the rectifier output. It is desirable to substantially eliminate the 15 ripple in the rectified current, since strong ripples tend to vibrate the recorder pen, and also beat reactions between the ripples may produce undesirable variations when the outputs of a plurality of rectifiers are combined.

20 The ripples may be eliminated by using condensers such as are commonly used across recorder coils. However, for high speed operation, these condensers tend to reduce the 25 signaling speed, and it would be preferable to use low pass filters. These filters should readily pass the low frequency corresponding to the keying pulses, but should not pass the relatively high ripple frequency.

In Figure 2, the low pass filters 139 are 30 shown as a conventional arrangement of series inductance and shunt capacitance elements. After the rectified current has passed through filter 139, a substantially pure direct current is obtained which varies in accordance with the transmitter keying. By connecting the rectifier outputs in parallel, each receiver contributes its portion of the received signal energy irrespective of the phase of the radio frequency currents.

40 So far as has been herein described in connection with Fig. 2 the arrangement is substantially identical to that of Fig. 1 with the exception of the fact that instead of using the spaced antennæ 1 and 3 of Fig. 1 we have 45 chosen to illustrate antennæ 101 and 103 of different directional characteristics located at the same point. If a recorder such as R_1 and R_2 of Fig. 1 be connected in series with the circuit at points 189 and 191 of Fig. 50 2, the results and the records obtainable will be substantially the same as are illustrated by the records "A" and "B" of Fig. 3 above described. The combined record "C" of Fig. 3 would be obtained if a recorder were substituted in place of resistance 135.

In Figure 2, we have chosen to show a modification which may be used for obtaining a tone signal after the rectified currents have been combined, and which will also produce a certain amount of limiting action which is desirable, since it reduces the effects of small variations in the combined rectified currents. The arrangement which is enclosed 55 within the dotted line rectangle is the limiter and modulator arrangement used for the

purpose of obtaining a tone signal in the tone circuit 175 to be hereinafter described. The ungrounded end of resistance 135 is connected through a bias battery 141 to the grid member 147 of the triode 143. The triode 70 143 has its energy and high potential supply for the plate 145 furnished through a battery 151 connected in series with a resistance 153. The plate circuit is completed through the filament member 149, which is grounded 75 at 155. The grid member 147 of the tube 143 is normally so biased by battery 141 that plate current will flow under conditions when no signal is being received. In this case, plate current flows thru the plate 145, the 80 filament 149, the battery 151 and the resistance 153. However, when signals are being received upon the antennæ 101 and 103 and directed from the points 189 and 191 of the rectifiers 129 and 131, to the point 133, due 85 to the voltage drop occurring across the resistance 135, the point 133 becomes negative with respect to its previous potential, and therefore the normal bias on the grid 147 of the tube 143 is overcome. It is to be understood 90 that the cut-off potential of the tube 143 depends upon both the voltage and polarity of the bias battery 141, and the characteristics of the tube 143.

It is also to be seen that when the tube 95 143 is passing plate current that the point where resistance 153 forms a connection with the plate 145 of the tube 143 and the bias battery 157 for the grid 163 of the tube 159 that this grid 163 becomes negative due to 100 the voltage drop occurring across resistance 153. In this case, with no signal on, the grid 163 of the tube 159 is carried to cut-off potential and the tube 159 fails to pass plate current. However, when the plate current 105 flow through the tube 143 is cut off due to signals being received upon the antenna members 101 and 103 and the point 133 of the resistance 135 becoming negative, the bias battery 157 carries the grid member 163 of 110 the tube 159 to a less negative value and the tube 159 at once starts to pass plate current, through the plate member 161, the filament 165, the ground return 167 and 179 and the plate potential supply 177. Connected to the 115 lead with the plate supply source 177 through a transformer 181 is an audio frequency oscillator 187 which feeds its energy into the primary 183 of the transformer 181 from 120 which the energy is transferred to the secondary 185. Also connected in the plate lead 161 is a transformer 169 having its primary winding 171 forming a part of the plate circuit and secondary 173 transferring energy 125 to a tone circuit 175. It is thus seen that the frequency of the audio oscillator 187 is heard in the tone circuit 175 during periods when the tube 159 is passing plate current, or in other words, at periods when signals are 130

being received upon either of the antenna members 101 or 103.

It may thus be noted that the functioning of the limiting and modulating arrangement illustrated in the dotted line rectangle as a part of Fig. 2 is determined by the fact of how negative the point 133 becomes and how this effects the grid 147 of the tube 143, since it is this characteristic which determines whether or not the tube 143 passes plate current, and likewise the size of the resistance 153 and the battery 157 which it will be noted should be of a size approximately the same as the battery 151 determines whether or not the tube 159 passes plate current. It will also be noted that if the limiter is adjusted so that the minimum signal will make the point 133 sufficiently negative to reduce the plate current of tube 143 to zero, a further increase in signal will have no effect on the tone output of transformer 169. Hence, if the combined rectifier currents vary over moderate limits, when proper adjustments are made these variations will not be repeated through to tube 159 which controls the tone output.

With further reference to Fig. 2, if the radio frequency amplifiers 105 and 107 are capable of delivering considerable energy, it is not necessary to convert the signal to lower frequency, as the output of the radio frequency amplifiers may be rectified directly by rectifiers 129 and 131. By using several stages of radio frequency amplification with several tuned circuits, a high degree of selectivity may be obtained. Such an arrangement would make it easy to filter the rectifier outputs, and this would make it particularly desirable for very high speed circuits, where the keying frequency may be several hundred cycles. It would also be desirable in some cases to convert the signal to an intermediate radio frequency instead of an audio frequency. This may be accomplished by substituting intermediate frequency amplifiers in place of the audio frequency amplifiers 113 and 115. The fundamental operation would be substantially the same as that described in connection with Fig. 2.

While only two receivers have been shown by Figs. 1 and 2, it is to be understood that any number of receivers may be used, using combinations of spaced antennæ of the same type, combinations of antennæ with different directive characteristics, or combinations of both spaced and directive antennæ. It has been determined experimentally that a particularly desirable combination of spaced antennæ for short waves, for example 15 to 30 meters, is to use three antennæ of the same directive characteristics spaced about 1,000 feet apart.

It will be clear that various modifications of the arrangement described and illustrated

by Figs. 1 and 2 and the description thereof may be made insofar as they fall fairly within the scope of the invention as defined by the following claims.

Having thus described our invention, what we claim is;

1. The method of avoiding the effects of fading on radio signals which includes, receiving the same signal at a plurality of separated points, separately rectifying the signal so received to produce current pulses of less than the received radio frequency, combining the current pulses from each of said systems, continuously generating a local alternating electromotive force, and utilizing the combined energies to turn on and off a current produced by the continuously generated local alternating electromotive force.

2. A radio signalling system including, a pair of antenna members each of different instantaneous response characteristics to a signal, a receiver associated with each of said antenna systems, an amplifier for amplifying the received signals from said receiver, a rectifier associated with each of said amplifiers, means for combining the outputs of said rectifiers, said means including a resistance in the combining circuit, a limiting device, means for controlling the operation of said limiting device by the resistance drop occurring in said resistance when signals are received, a modulator, a tone circuit, and means provided by said limiting device for limiting the response of said modulator in said tone circuit to a substantially constant value irrespective of moderate intensity variations when signals are being received upon said antenna members and the combined rectified signals produce a resistance drop across said resistance equal to or greater than the limiting value of said limiting device.

3. In combination, in a system for reducing fading, a plurality of separated energy collectors, means for reducing the frequency of energy collected on said collectors, means for combining the energies of reduced frequency, an impedance, means for applying the combined energies to said impedance whereby voltage variations arise across said impedance in accordance with the combined energies passed therethrough, an electron discharge device having an anode a cathode and a control electrode, a source of undulatory electromotive force coupled to the anode circuit of said electron discharge device, an output circuit coupled to said anode circuit, and means for coupling said impedance to the control electrode of said electron discharge device whereby current, corresponding in frequency to the alternating electromotive force generated flows in said output circuit in accordance with the potential applied to said control electrode from said impedance.

4. In a system of the character described, an energy collector for collecting modulated

high frequency electrical waves, means for obtaining currents corresponding to the modulation of said waves, a resistance, means for passing said modulation currents through said resistance whereby potentials arise thereacross corresponding in value to the currents applied, an electron discharge device having an anode circuit and an output circuit coupled to said anode circuit, a local generator of alternating current coupled to said anode circuit, and means coupling said resistance and said electron discharge device whereby the internal impedance of said electron discharge device is varied in accordance with the voltage variations across said resistance, whereby alternating current from said local source flows in said output circuit in varying degree as the conductivity of said electron discharge device is varied.
